(57) **CLAIM**

We claim the ornamental design for a wireless charger case for electronic communications device, as shown and described.

DESCRIPTION

FIG. 1 is a front perspective view of a wireless charger case for electronic communications device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and,

FIG. 9 is an exploded front perspective view wherein the wireless charger case for electronic communications device is shown with an example environmental electronic device. The broken lines in the figures depict environmental subject matter that forms no part of the claimed design.
